WALTER S. RYAN, OF INDIANAPOLIS, INDIANA, ASSIGNOR TO RYAN CONSTRUCTION COMPANY, OF MUNCIE, INDIANA, A CORPORATION.

DEVICE FOR MAKING AN ELECTRICAL CIRCUIT OR CIRCUITS.

No. 926,680.

Specification of Letters Patent.

Patented June 29, 1909.

Application filed March 4, 1907. Serial No. 360,361.

To all whom it may concern:

Be it known that I, WALTER S. RYAN, a citizen of the United States, residing at the city of Indianapolis, in the county of Marion, State of Indiana, have invented a new and useful Device for Making an Electrical Circuit or Circuits, of which the following is a specification.

My invention relates to improvements in devices for making electrical circuits wherein a fluid electrical conductor contained in a movable switch member is the medium of connection between the terminals.

The features of my invention include a pivoted duplex switch bar having a fluid electrical conductor so retained and having contacts so positioned therein, and terminal post connections adapted to be engaged by said contacts so that with the oscillation of the switch-bar circuits through the terminals may be established consecutively and means actuated by the switch-bar to cause the oscillation of the latter, at regular intervals.

The invention is shown herein embodied in a sign-flasher by the operation whereof the alternate illumination successively and the extinguishment of all simultaneously of two series or banks of incandescent lamps, arranged for purposes as a sign are accomplished.

The objects of this invention are accomplished by the mechanism described in this specification, pointed out in the appended claims, and illustrated in the accompanying drawings.

Similar characters of reference refer to corresponding parts throughout the several views, in which—

Figure 1 is a side view and Fig. 2 is a plan view of my invention; in the latter view the non-conductive diagonal supports being not shown in solid black. Fig. 3 is a longitudinal vertical sectional view of the switch-bar removed. Fig. 4 is a detached plan view of the switch-bar removed, all but a small portion of the shaft 5 being broken away. Fig. 5 is a transverse sectional view of the switch-bar taken on the line 5—5 Fig. 1; Fig. 6 is a transverse sectional view of the switch-bar taken on the line 6—6 Fig. 1. Fig. 7 is a transverse sectional view of the diagonal support taken on the line 7—7 Fig. 1. Fig. 8 is a transverse central sectional view of Fig. 1 taken from the direction as indicated

by the arrow, the non-conductive diagonal supports being not shown in solid black. Fig. 9 is a diagrammatic view showing the system of wiring, the parts being distorted in form and their relative positions changed. 60

Mounted on the base 1 having proper dimensions and made of material of suitable solidity, are the diagonal supports 2 made of non-conductive material such as slate, and disposed with reference to each other at an angle of substantially forty five degrees. These supports are retained in accurate alinement and rigid position by the standard 3 having suitable feet bolted to the base, the intervening plate of insulation 3^a being interposed, and the standard having its vertical face bolted to the rear sides of the diagonal supports. The vertical leg of this standard is extended upwardly and supports the transverse-box 4 in which is journaled a suitable shaft 5, its forward end being rigidly secured to the switch-bar and its rear end having a rigidly secured hub 6^a to which is secured the segments 6 insulated therefrom by the hard-fiber collar 6^b, as plainly shown in Fig. 8. 70

Positioned perpendicularly below the line of the peripheries of the segments are the solenoids 7 and 8 rigidly sustained on suitable standards. The cores 9 and 10 of these solenoids, respectively, are loosely secured 85

at their upper ends to suitable flexible cords which engage the peripheries of the segments and are secured thereto at their upper ends. These flexible cords consist preferably of 90 chains 6^c and a shallow groove is provided in each of the segments as suitable guides therefor. With this arrangement it will be readily observed that as the cores may be alternately actuated, the switch-bar will be accordingly oscillated, the purpose whereof will be hereinafter more fully set forth. The body-portion 11 of this switch-bar is constructed of a conductive metal that will be unaffected by the contact therewith of 95

quicksilver; aluminium has been employed in this construction on account of its lightness of weight. Iron or steel may be used as well. The enlarged central part of the body portion 11 is thickened on its rear side where the shaft 5 is rigidly secured, and the upper and lower portions are formed so as to provide the walls of the chamber 12; the extended portions form upper and lower ribs, each pair integrally joined at their outer 100 105 110

ends, whereby the long-chambers 13 and 14 are formed. At the points where these long-chambers communicate with the central chamber 12, the partial partitions 15 are 5 provided, each of the same length, extending angularly toward the upper part of the chamber 12 to leave a space between their ends. Midway between the ends of these partitions 15 is the partial partition 16 10 formed integrally with the upper portion of the shell 11 and extending downwardly midway between and slightly below the plane of the ends of the partitions 15. Leading from the lower part of the chamber 12 in opposite directions, are the channels 17 and 18, 15 and which open into the extreme ends of the chambers 13 and 14 respectively, as plainly shown in Fig. 3.

19 designates a smaller channel extending 20 continuously from end to end through the upper part of the metal portion 11, its opposite ends communicating with the extreme ends of the long-chambers 13 and 14; there is also the channel 19^a from channel 19 down 25 through the partial partition 16.

20 and 21 designate plates made of non-conducting material, preferably of hard-fiber, rabbeted upon their inner faces so that when they are secured into snug contact on 30 the front and rear sides of the body-portion of the switch-bar they form the sides of the chambers 13 and 14, the chamber 12, the channels 18, 19 and 119, as shown in Fig. 3 and Fig. 5.

35 22 designates suitable metallic bolts which serve as means to securely draw and maintain these side-plates 20 and 21 securely in position, and also as contact-posts, which will be hereinafter referred to.

40 23 designates a suitable screw-plug which normally closes an opening in the plate 20 communicating with the chamber 12, affording access for the introduction into said chamber of a quantity of liquid conductive material. Quicksilver has been found to be preferable. Preparatory to depositing the quicksilver in the switch-bar it is placed in the inclined position as shown in Fig. 1. When such quantity of quicksilver has been 50 poured into the switch-bar that all of the contact-posts 22 in the chamber 13 have been submerged and the dotted line A—A as shown in Fig. 3 has been reached, the screw-plug 23 is secured in its normal position and 55 the switch-bar is complete.

It is obvious that when the switch-bar is oscillated and brought into position reverse to that shown in Fig. 1, the quicksilver will flow downwardly from the long-chamber 13 60 over the partial partition 15, and, deflected by the partial partition 16 will pass into the chamber 12 and then into the channel 18, and from thence into the then lower end of the long-chamber 14 to the extent desired, 65 and as shown in its filling of the long-cham-

ber 13. By providing the air-channels 19 and 19^a, a vacuum in either end of the switch bar is prevented and the free and unobstructed flow of the quicksilver is at all times insured. The regulation of the speed of the 70 flow of the quicksilver from the chamber 12 is accomplished by manipulation of the screw-gages 25, as shown in Fig. 6 and in Fig. 1, which obstruct the channels 17 and 18.

Arranged on each side of the diagonal supports, are the series of resilient contact-strips 26 and 27. These contact-strips are of the general form as seen in the detached transverse sectional view shown in Fig. 7, and are so disposed that when the switch-bar is drawn downwardly and comes to rest on the cushion 24, the contact-posts 22 have come into direct contact with these strips which are secured by metallic bolts passing through the diagonal supports 2, and provided at their free ends with suitable means whereby proper wiring may be secured thereto, as will be hereinafter referred to.

85 The resilient contact-strips 28 and 29 are extended in length and are formed with suitable curvature longitudinally and transversely so that in the oscillation of the switch-bar the severance of the contact of one, and the making of contact by the other with the contact-posts 22 nearest the fulcrum will occur when the switch-bar reaches a horizontal position.

90 The device above described is designed for use as a sign flasher, and the diagrammatic view shown in Fig. 8, discloses the system of 100 the wiring and the courses of the circuits. By reference to this view, taken in connection with the other views, the operation of my invention may be readily understood.

105 When the switch-bar is in the position shown in Fig. 1, an ordinary switch 30^a is closed, thereby closing the circuit. The current passes along the wire 30 through the standard 3, the shaft 5 and the body-portion 11 of the switch-bar; the quicksilver has 110 flown from the chamber 12 into the channel 17 and risen in the long-chamber 13, and as it contacts with the first one of the series of contact-posts 22 the current is caused to pass through the wire and lamp 31, the wire 32, thence through wire 34. As the quicksilver 115 in seeking its level, rises gradually in the long-chamber 13 and contacts successively with the contact-posts 22, the series of lamps properly wired to the strips 26 are consecutively illuminated. The quicksilver having come in contact with the last of the contact posts 22, the current then passes through the contact-strip 28, the wire 35, the solenoid 7, and the wires 33 and 34. The core 9 being 125 magnetized the switch-bar is immediately actuated; the impulse received pulls it away from the position just described, thereby severing contact with the posts 22 and the contact-strips 26, thus opening substantially 130

simultaneously each of said circuits. As the switch-bar passes the horizontal line, in its oscillation, the connection between the extreme interior contact-post 22 and the contact-strip 28 is severed. As the switch-bar, by the impulse given it, and by virtue of its inertia, continues its movement and reaches its normal reverse position resting on the cushion, the quicksilver then flows from the 10 long-chamber 13 into the chamber 12 and then into the channel 18, thence continuing to flow into the long-chamber 14 and to seek its level, as hereinbefore described. In its rise, as it comes into contact with the first 15 one of the contact posts 22, the current is afforded a circuit through the wire and lamps 36, the wire 37, and thence along the wire 34. As the quicksilver proceeds in seeking its level and gradually rises in the long-chamber 20 14 it comes into contact with the contact-posts 22 consecutively, and the series of lamps properly wired to the contact-strips 27 are consecutively illuminated. The quicksilver having come into contact with the last 25 25 of the contact-posts 22, the current then passes through the contact-strip 29, the wire 38, the solenoid 8 and the wires 33 and 34. The core 10 being magnetized the switch-bar is immediately actuated, and the 30 impulse so received pulls it away from its position thereby severing contacts with the contact-posts 22 and the contact-strips 27, thus opening substantially simultaneously each of the circuits. As the switch-bar 35 passes the horizontal line in its oscillation, contact between the last contact-post 22 and the contact-strip 29 is severed. As the switch-bar, by the impulse given it and by virtue of its inertia continues its movement 40 and again assumes the position as shown in Fig. 1, the quicksilver flows from the long-chamber 14 against the deflector-partition 16 into the channel 17 and rises in the long-chamber 13, whereupon the operation here- 45 inbefore described is repeated.

What I claim as my invention, and desire to secure by Letters Patent of the United States, is—

1. An electric switch including a switch-bar fulcrumed in the middle and vertically oscillatory and provided at its fulcrum with a chamber and two cavities extending from said chamber to the ends of said switch-bar, said cavities being parallel with one above 50 the other and connected at the outer ends of the switch-bar, a liquid electrical conductor in said switch-bar and adapted to flow through the lower cavities from the central chamber to the outer ends in alternate directions as the switch-bar is oscillated, contact points extending into the upper cavities substantially as set forth, an electric circuit, terminals mounted to be touched by the contact points in said switch-bar nearest its fulcrum, electro responsive devices in said cir- 55

cuit to be energized by the current flowing through the said terminals and the contact points in said switch-bar nearest its fulcrum, to oscillate said switch-bar after each operation thereof. 70

2. An electric switch including a switch-bar fulcrumed in the middle and vertically oscillatory and provided at its fulcrum with a chamber and two cavities extending from said chamber to the ends of said switch-bar 75 said cavities being parallel with one above the other and connected at the outer ends of the switch-bar, a channel extending the full length of said switch-bar and above said cavities and in communication therewith at 80 each end and at the middle of the switch-bar, a liquid electrical conductor in said switch-bar and adapted to flow through the lower cavities from the central chamber to the outer ends in alternate directions as the 85 switch-bar is oscillated, contact points extending into the upper cavities substantially as set forth, an electric circuit, terminals mounted to be touched by the contact points in said switch-bar nearest its fulcrum, electro responsive devices in said circuit to be energized by the current flowing through the 90 said terminals and the contact points in said switch-bar nearest its fulcrum, to oscillate said switch-bar after each operation thereof. 95

3. An electric switch including a switch-bar fulcrumed in the middle and vertically oscillatory and provided at its fulcrum with a chamber and two cavities extending from said chamber to the ends of said switch-bar, 100 said cavities being parallel with one above the other and connected at the outer ends of the switch-bar, a liquid electrical conductor in said switch-bar and adapted to flow through the lower cavities from the central chamber to the outer ends in alternate directions as the switch-bar is oscillated, contact points extending into the upper cavities substantially as set forth, an electric circuit, 105 terminal points mounted so as to be touched by the contact-points in said switch-bar nearest its fulcrum, a shaft on which said switch-bar is fulcrumed, a pair of opposite segments secured on said shaft, a solenoid in connection with each segment and in the said circuit. 110

4. An electric switch including a switch-bar fulcrumed in the middle and vertically oscillatory and provided at its fulcrum with a chamber and two cavities extending from said chamber to the ends of said switch-bar 120 said cavities being parallel with one above the other and connected at the outer ends of the switch-bar, a liquid electrical conductor in said switch-bar and adapted to flow through the lower cavities from the central chamber to the outer ends in alternate directions as the switch-bar is oscillated, devices to restrain and to gage the flow through said 125 lower cavities of the liquid conductor, con- 130

tact points extending into the upper cavities substantially as set forth, an electric circuit, terminals mounted to be touched by the contact points in said switch-bar nearest its fulcrum, electro responsive devices in said circuit to be energized by the current flowing through the said terminals and the contact points in said switch-bar nearest its fulcrum, to oscillate said switch-bar after each operation thereof.

5. An electric switch including a switch bar centrally fulcrumed and vertically oscillatory and provided at its fulcrum with a chamber, two cavities extending from said chamber to the ends of said switch-bar and being parallel one above the other and connected at the outer ends of the switch-bar, a liquid electrical conductor in said switch-bar and adapted to flow through the lower cavities from the central chamber to the outer ends in alternate directions as the switch-bar is oscillated, a series of contact-points with which the liquid electrical conductor as it seeks a level consecutively comes in contact, an electric circuit, terminals mounted to be touched by the contact points in said switch bar nearest its fulcrum, means energized by the circuit established by the switch-bar through said contact nearest the said fulcrum for oscillating the switch-bar after each operation thereof.

6. An electric switch including a switch bar centrally fulcrumed and vertically oscillatory and provided at its fulcrum with a chamber, two cavities extending from said chamber to the ends of said switch-bar and being parallel one above the other and connected at the outer ends of the switch-bar, a liquid electrical conductor in said switch-bar and adapted to flow through the lower cavities from the central chamber to the outer ends in alternate directions as the switch-bar is oscillated, a series of contact-points with which the liquid electrical conductor as it seeks a level consecutively comes in contact, an electric circuit, terminals mounted to be

touched by the contact-points in said switch-bar nearest its fulcrum, means energized by the circuit established by the switch-bar through said contact nearest the said fulcrum for oscillating the switch - bar after each operation thereof, terminals adapted to be touched by the contact-points carried by the switch-bar other than those nearest the fulcrum thereof, substantially as described.

7. An electric switch including a switch-bar fulcrumed in the middle and vertically oscillatory and provided at its fulcrum with a chamber, two cavities extending from said chamber to the ends of said switch-bar, said cavities being parallel with one above the other and connected at the outer ends of the switch-bar, a liquid electrical conductor in said switch-bar and adapted to flow through the lower cavities from the central chamber to the outer ends in alternate directions as the switch-bar is oscillated, contact points extending into the upper cavities substantially as set forth, an electric circuit, terminal points mounted so as to be touched by the contact-points in said switch-bar nearest its fulcrum, a shaft on which said switch-bar is fulcrumed, a pair of opposite segments secured on said shaft, a solenoid in connection with each segment and in the said circuit, a support underneath the switch-bar having stops thereon at each side of the center against which the switch-bar will rest at the end of each movement thereof, terminals carried by said support and having resilient contact strips connected thereto to yieldingly engage and disengage the contact-points carried by the switch-bar, substantially as described.

In testimony whereof I have hereunto subscribed my name to this specification, in the presence of two subscribing witnesses.

WALTER S. RYAN.
